There is disclosed a developing processing method and apparatus in which developing processing is carried out with a developing solution being jetted toward an emulsion surface of a photosensitive material from jetting holes of a blowoff chamber. Only one blowoff chamber is disposed in a developing tank and conveying roller sets are disposed at both sides of the blowoff chamber. The photosensitive material is horizontally conveyed above the blowoff chamber by the conveying roller sets. Due to the number of components of the developing processing tank being thus reduced, the apparatus can be made small in size. Positions where the photosensitive material is nipped by the roller sets are located within a processing solution, and therefore, there is no possibility of the photosensitive material being nipped and conveyed in a state in which outer peripheral surfaces of the rollers are wet non-uniformly with the processing solution. As a result, non-uniform processing is prevented.

DEVELOPING PROCESSING METHOD AND APPARATUS

BACKGROUND OF THE INVENTION

1. Field of the Invention

The present invention relates to a developing processing apparatus in which a silver halide color photographic light-sensitive material (hereinafter referred to as a photosensitive material) is subjected to developing processing, and a developing processing method in which the developing processing apparatus can be applied.

2. Description of the Related Art

An example of a developing processing method and apparatus is disclosed in, for example, U.S. Pat. Nos. 5,355,190 and 5,389,994 in which a processing solution is jetted from jetting holes of a blowoff chamber, which blowoff chamber is disposed on a conveying path of a photosensitive material, toward an emulsion surface of the photosensitive material, and the photosensitive material is subjected to developing processing while being conveyed horizontally, and further, a processing solution in a processing tank is agitated.

In this developing processing method and apparatus, a plurality of blowoff chambers are disposed in one processing tank and conveying rollers are located at both sides of each blowoff chamber. Accordingly, there is a limit to making the apparatus small in size.

Further, in order to obtain desired photographic properties, when a jetting region is extended by making the blowoff chamber larger, the apparatus increases in size. As a countermeasure against the foregoing, when an attempt to make the apparatus small in size is made by decreasing diameters of the conveying rollers which are disposed at both sides of the blowoff chamber, conveying torque decreases, which results in occurrence of jamming.

On the other hand, when the blowoff chambers and the conveying rollers are independently mounted in the processing tank, respective positions in a vertical direction of the apparatus or the direction in which the photosensitive material is conveyed are dislocated. Therefore, each time maintenance (for example, cleaning) of the processing tank is carried out, the photographic properties of the photosensitive material change.

SUMMARY OF THE INVENTION

In view of the above-mentioned circumstances, an object of the present invention is to obtain desired photographic properties and realize a small-size developing processing apparatus.

A first aspect of the present invention is a developing processing apparatus equipped with at least one blowoff chamber having jetting holes from which a processing solution is jetted toward an emulsion surface of a photosensitive material, wherein the one blowoff chamber is disposed in a processing tank, roller sets are located at both sides of the blowoff chamber, the photosensitive material is horizontally conveyed above the blowoff chamber, and positions where the photosensitive material is nipped by the roller sets are located within the processing solution.

The apparatus of the first aspect is a photosensitive material processing apparatus provided to process a photosensitive material and having a processing tank in which a processing solution is filled, and the photosensitive material processing apparatus comprises: at least one blowoff chamber disposed in the processing tank and having jetting holes

from which the processing solution is jetted toward an emulsion surface of the photosensitive material; and roller sets located at both sides of the blowoff chamber and conveying the photosensitive material horizontally above the blowoff chamber, wherein positions where the photosensitive material is nipped by the roller sets are located within the processing solution filled in the processing tank.

According to the first aspect of the present invention, developing processing is carried out in such a manner that a processing solution is jetted out from the jetting holes of the blowoff chamber toward the emulsion surface of the photosensitive material.

Only the one blowoff chamber is disposed in the processing tank such as a developing tank or a bleach-fixing tank and the roller sets are disposed at both sides of the blowoff chamber. The photosensitive material is horizontally conveyed above the blowoff chamber by the roller sets. By reducing the number of components of the processing tank as described above, the apparatus can be made in small size.

Further, positions where the photosensitive material is nipped by the roller sets are located within the processing solution, and there is no possibility of the photosensitive material being nipped and conveyed by the roller sets in such a manner that outer peripheral surfaces of the rollers are wet non-uniformly with the processing solution. As a result, non-uniform processing is prevented.

A second aspect of the present invention is structured in such a manner that, in the above-described first aspect, the roller sets are mounted integrally in the processing rack set in the processing tank. Accordingly, there is no possibility of positions where the photosensitive material is nipped by an upstream-side roller set and a downstream-side roller set becoming dislocated and a distance between the roller sets changing thereby.

A third aspect of the present invention is structured in such a manner that, in the above-described first aspect, the blowoff chamber is, together with the roller sets, formed integrally with the processing rack. Accordingly, a positional relationship between the roller sets and the blowoff chamber, and an interval between the photosensitive material nipped and conveyed by the roller sets and a surface of the blowoff chamber 22 from which the processing solution is jetted can be maintained fixedly.

A fourth aspect of the present invention is structured in such a manner that, in the above-described first aspect, a diameter of each of the roller sets is in the range of 10 mm to 20 mm and a dimension of the blowoff chamber in a direction in which the photosensitive material is conveyed is in the range of 50 mm to 120 mm. It suffices that, in the present invention, a diameter of a lower roller of the roller set (which lower roller is disposed at the side of the blowoff chamber) is in the above-described range, and respective roller diameters of upper and lower rollers may be the same or different from each other. Further, it is necessary that a roller diameter of the upper roller be greater than or equal-to that of the lower roller.

By setting the diameters of the roller set as described above, necessary torque can be maintained. Accordingly, even a photosensitive material having a large widthwise dimension can be processed without causing jamming. Further, the dimension of the blowoff chamber in the direction in which the photosensitive material is conveyed is in the range of 50 mm to 120 mm, and therefore, a sufficient jet agitation effect can be achieved and desired photographic properties can be obtained.

A fifth aspect of the present invention is a developing processing method in which a processing solution is jetted

toward an emulsion surface of a photosensitive material by a blowoff chamber having jetting holes formed therein, wherein the one blowoff chamber is disposed in a processing tank and the photosensitive material is processed while being horizontally conveyed above the blowoff chamber by roller sets, which are disposed at both sides of the blowoff chamber and are formed in such a manner that positions where the photosensitive material is nipped by the roller sets are located within the processing solution.

Sixth, seventh, eighth, and ninth aspects of the present invention are structured in a manner similar to the second to fifth aspects of the present invention in the above-described sixth aspect.

BRIEF DESCRIPTION OF THE DRAWINGS

FIG. 1 is an exploded perspective view of a developing processing apparatus according to an embodiment of the present invention.

FIG. 2 is a cross-sectional side view of the developing processing apparatus according to the embodiment of the present invention.

FIGS. 3A and 3B are enlarged plan views which each show arrangement of jetting holes in the developing processing apparatus according to the embodiment of the present invention.

FIGS. 4A and 4B are graphs which each show a distance between a jetting hole and a paper (that is, a photosensitive material), and flow velocity.

FIG. 5 is a graph which shows a relationship between conveying torque and photographic property.

DESCRIPTION OF THE PREFERRED EMBODIMENTS

FIGS. 1 and 2 each show a developing processing apparatus 10 according to an embodiment of the present invention.

The developing processing apparatus 10 is a system in which a photosensitive material is subjected to developing processing while being conveyed horizontally (in the present invention, the photosensitive material means a silver salt photographic light-sensitive material). A paper P serving as the photosensitive material is processed in a developing tank 12, a bleach-fixing tank 14, a plurality of washing tanks 16, and a drying section 18 in that order while being horizontally conveyed, and is then discharged into a tray 20.

Here, a blowoff chamber 22 which is a characterizing portion of the present invention is provided both in the developing tank 12 and in the bleach-fixing tank 14. The blowoff chambers 22 provided in the two tanks have the same basic structures, and therefore, a description will be given, as an example, of the blowoff chamber disposed in the developing tank 12. In the present invention, the blowoff chamber may be provided in one or both of the developing tank and the bleach-fixing tank.

A liquid-distributing block 24 is provided on a bottom surface of the developing tank 12. A developing solution is sent to the liquid-distributing block 24 from a circulating pump 26 via a liquid-distributing pipe 28. The liquid-distributing pipe 28 branches out into three connecting pipes 30 and the liquid-distributing block 24 is provided with discharging pipes 32 communicating with the connecting pipes 30 respectively.

On the other hand, recovery holes 34 are formed in a side wall of the developing tank 12 and used to regulate a liquid level of the developing solution. The developing solution is

recovered into an auxiliary tank 36 via the recovery holes 34. The developing solution recovered into the auxiliary tank 36 is, if necessary, replenished with a replenishing agent and water, and then delivered from a return pipe 27 via the circulating pump 26, and thereafter blown off again from the discharging pipes 32 of the liquid-distributing block 24.

The blowoff chamber 22 is set on the top surface of the liquid-distributing block 24. Three water absorption openings 38 are formed in the bottom surface of the blowoff chamber 22 at the same intervals as those of the discharging pipes 32 and are provided to communicate with the discharging pipes 32. The three water absorption openings 38 are linked via a rectangular storage portion 40 disposed at an upper side of the water absorption openings 38. The developing solution discharged from the discharging pipes 32 reaches the storage portion 40 at a predetermined hydraulic pressure.

An open side of the storage portion 40 is closed by a jetting panel 42 in which a plurality of jetting holes 44 are formed so as to pass therethrough and the developing solution jetted from the jetting holes 44 is jetted upon an emulsion surface of the paper P.

On the other hand, a processing rack 46 is set on the top side of the developing tank 12. The processing rack 46 is equipped with: an insertion roller pair 48 which guides an exposed paper P from an upper side to a lower side; a set of three conveying rollers 50, 52, and 54, which are located at the downstream side of the blowoff chamber 22 in a direction in which the paper P is conveyed and conveys the paper P to above the jetting holes 44 while correcting the position of the paper P conveyed obliquely by the insertion roller pair 48 into a horizontal position; and a set of conveying rollers 56 for conveying, to the bleach-fixing tank 14, the paper P conveyed above the jetting holes 44 and subjected to developing processing.

Due to the rollers being mounted in the processing tank 46 as described above, there is no possibility of positions where the paper is nipped by an upstream-side roller pair and a downstream-side roller pair becoming dislocated and a distance between the roller pairs changing thereby.

Further, the position where the paper P is nipped by the conveying rollers 52 and 54 and the position where the paper P is nipped by the conveying roller pair 56 are located below a liquid level L of the developing solution. When the paper P is nipped by these rollers, the distance between the jetting holes 44 and the paper P is set to be 2.0 mm to 20.0 mm, and in the present embodiment, it is set to be 5.0 mm.

By setting the distance between the jetting holes 44 and the paper P as described above, non-uniform processing of the paper P is prevented in a region of the paper P facing the jetting holes 44 and its peripheries, to thereby improve photographic properties as can be seen by eye from the schematic diagram shown in FIG. 3B.

The positions where the paper P is nipped by the three conveying rollers 50, 52, and 54 are located below the liquid level L of the developing solution. The paper P is nipped by these rollers after having been immersed in the developing solution, and therefore, non-uniform processing is prevented.

Next, the blowoff chamber 22, the jetting holes 44, and the conveying rollers will be described in detail.

As shown in FIG. 3A, the hole diameter of each jetting hole 44 is preferably 0.5 mm to 0.9 mm, and in the present embodiment, it is set to be 0.7 mm. In this case, clogging does not easily occur and a processing solution can be jetted from the jetting holes stably for a long period of time.

Further, the jetting holes 44 are arranged at intervals of 3.0 mm to 4.5 mm in a longitudinal direction of the jetting panel 42 (that is, in a transverse direction of the photosensitive material). The jetting holes 44 are disposed in plural rows in such a manner that the rows of the jetting holes 44 form a staggered arrangement. In the present embodiment, these holes are arranged at intervals of 4.5 mm (from the centers of the holes) in the longitudinal direction of the jetting panel 42. Adjacent three rows of the jetting holes 44 are located at different positions from each other to form the staggered arrangement, and the three rows are formed repeatedly on the jetting panel 42. As a result, when seen from the direction in which the paper P is conveyed, the interval of the jetting holes 44 is substantially set to be 4.5 mm/3=1.5 mm.

When the intervals of the jetting holes 44 in the transverse direction of the paper P are substantially made narrower as described above, non-uniform processing does not occur and desired photographic properties can be obtained.

Further, the jetting holes 44 are arranged at intervals of 6.0 mm in the direction in which the paper P is conveyed and the total number of the jetting holes is 720, that is, 12 rows of jetting holes are provided in the direction in which the paper P is conveyed and 60 jetting holes are arranged per row in the transverse direction of the paper P. Here, a pump which pumps 20 liters per minute is used as the circulating pump 26. A jet flow amount of the pump for each of the jetting holes 44 is 14.2 liters per minute and this value becomes 854.6 mm/s by calculation in terms of flow velocity.

FIGS. 4A and 4B show simulation results obtained by calculation of the distribution of jet flow velocity in the transverse direction of the paper P at a position which is 0.1 mm away from the emulsion surface. FIG. 4A shows an example in which the jetting holes 44 are arranged to form a repetition of a two-row zigzag pattern with adjacent jetting holes 44 being disposed at an interval of 10 mm, and FIG. 4B shows an example in which the jetting holes 44 are arranged to form a repetition of a three-row zigzag pattern with adjacent jetting holes 44 being disposed at an interval of 4.5 mm. In the present invention, the three-row zigzag pattern is more preferable than the two-row zigzag pattern. It can be seen from FIGS. 4A and 4B that, in the three-row zigzag pattern, non-uniform processing does not occur and desired photographic properties are obtained.

As described above, even when a conventional circulating pump 26 is used, the jet flow velocity can be increased depending on a setting pattern of the jetting holes 44, and an ability to agitate the developing solution can be maintained.

On the other hand, the dimension B of the blowoff chamber 22 in the direction in which the paper is conveyed is in the range of 50 mm to 120 mm. Respective diameters of the conveying rollers 52 and 54, which are disposed at the upstream side of the blowoff chamber 22 in the direction in which the paper is conveyed, and the diameter of the conveying roller 56 disposed at the downstream side of the blowoff chamber 22 are each in the range of 10 mm to 20 mm (preferably, 15 mm).

Further, developing processing time is in the range of 10 to 15 seconds and conveying speed is in the range of 7 to 20 mm/s. As compared with a conventional small-size developing processing apparatus, high-capacity processing becomes possible.

As shown in FIG. 5, when a paper having a large widthwise dimension (for example, a paper of A4-size(210×297 mm)) is used, a conveying torque of a conveying roller of at least 1 kg is required. By setting the diameter of the

conveying roller to be 15 mm, a torque of 1.5 kg can be maintained and no jamming occurs. As a result, a desired photographic property (density) can be obtained.

Further, although in the present embodiment, the blowoff chamber 22 is provided in the developing tank 12, it may also be mounted in the processing rack 46. As a result, a positional relationship between a roller pair (or set) and the blowoff chamber 22 and an interval between the paper P nipped and conveyed by the roller pair and a surface of the blowoff chamber 22 from which the processing solution is jetted can be maintained fixedly.

[Composition of light-sensitive material]

A composition of a silver halide color photographic light-sensitive material which is preferably combined with the developing processing apparatus of the present invention will be described hereinafter in detail.

In the present invention, a silver halide emulsion layer containing a yellow coupler is preferably provided at a position further away from a substrate than at least one of a silver halide emulsion layer containing a magenta coupler and a silver halide emulsion layer containing a cyan coupler. Further, the silver halide emulsion layer containing a yellow coupler is more preferably provided at a position further away from the substrate than both of the other silver halide emulsion layers from the standpoint of color development, rapidity of desilvering, reduction of residual color caused by sensitizing dyes, and the like. In the present invention, it is preferable to use a silver halide color photographic light-sensitive material in which the silver halide emulsion layer containing a cyan coupler is coated on a substrate, the silver halide emulsion layer containing a magenta coupler is coated on the cyan coupler-containing layer, and the silver halide emulsion layer containing a yellow coupler is finally coated on the magenta coupler-containing layer.

A coating thickness of a photographic composition layer in the present invention is preferably in the range from 1.0 μm to 9.0 μm , more preferably in the range from 2.0 μm to 8.0 μm , and most preferably in the range from 3.5 μm to 7.0 μm . The coating thickness of a photographic composition layer in the silver halide color photographic light-sensitive material used in the present invention indicates a thickness of an unprocessed photographic composition layer located above the substrate. Concretely, the coating thickness of a photographic composition layer can be obtained by any one of the following methods: a method in which the coating thickness is obtained by cutting the silver halide color photographic light-sensitive material perpendicular to the substrate and observing a cut surface by an electron microscope; and a method in which the coating thickness is calculated from an amount of coating (g/m^2) of each of components in the photographic composition layer and a specific gravity thereof. The specific gravity of typical gelatin used for photographic processing is 1.34 g/ml and the specific gravity of silver chloride grains is 5.59 g/ml. The specific gravity of other oleophilic additives can also be measured.

The form of the silver halide grains contained in a photographic emulsion of a light-sensitive material preferably used in the developing processing apparatus of the present invention can be a form of a normal crystal such as cube, octahedron or tetradecahedron, or a form of irregular crystal habit such as spheroid or tablet, or a form of composite type.

A pair of parallel surfaces of a tabular grain, which are placed perpendicular to a direction along the thickness of the tabular particle, is called a principal plane. In the developing processing apparatus of the present invention, it is preferable

to process a light-sensitive material including a photographic emulsion which contains a tabular grain having (111) plane as the principal plane or a tabular grain having (100) plane as the principal plane. Further, in the present invention, a light-sensitive material in which a photographic emulsion contains silver halide tabular grains having (100) plane is more preferably used.

Silver halide tabular grains having (111) plane and (100) plane, which are used for the light-sensitive material of the present invention, will be described in detail.

There have been disclosed processes in which various crystal habit controlling agents are used for the preparation of tabular grains. Among these crystal habit controlling agents, compounds described in Japanese Patent Application Laid-Open (JP-A) No. 2-32 (examples of compounds 1 to 42) are preferably used, and crystal habit controlling agents 1 to 29 described in JP-A No. 6-333780 are particularly preferable. However, the present invention is not limited to the same.

The tabular grains having (111) planes are obtained by forming two sets of parallel twinned crystal planes. The formation of the twinned crystal planes depends on a temperature, a dispersion medium (gelatin), halogen concentration, and the like. Therefore, it is necessary to set a proper value for each of these conditions. When the crystal habit controlling agent is allowed to be present at the time of nucleus formation, the concentration of gelatin is preferably in the range from 0.1 to 10%. The concentration of chloride is set to be 0.01 mol/L or more, preferably 0.03 mol/L or more.

It is preferably that no crystal habit controlling agent be used during nucleus formation in order that the grains be made monodisperse, which is disclosed in JP-A No. 8-184931. When no crystal habit controlling agent is used during nucleus formation, the concentration of gelatin is set in the range from 0.03 to 10%, preferably in the range from 0.05 to 1.0%. The concentration of chloride is set in the range from 0.001 to 1 mol/L, preferably in the range from 0.003 to 0.1 mol/L. The temperature of nucleus formation can be set arbitrarily in the range from 2 to 90° C., preferably in the range from 5 to 80° C., and most preferably in the range from 5 to 40° C.

At the initial stage of nucleus formation, nuclei of tabular grains are formed, and immediately after the formation of nuclei, a large number of nuclei other than those of tabular grains are placed in a reaction vessel. Accordingly, it becomes necessary to use a technique in which ripening is conducted after the nucleus formation, and only nuclei of the tabular grains are allowed to remain and the others are removed. When ordinary Ostwald ripening is carried out, the nuclei of tabular grains are also molten and disappear. Therefore, the nuclei of tabular grains decreases, and the size of the resulting tabular grains thereby increases. In order to solve this problem, a crystal habit controlling agent is added. Particularly with gelatin phthalate being used together, the effect of the crystal habit controlling agent is enhanced to prevent melting of the tabular grains. During the ripening, pAg is particularly important and is preferably in the range from 60 to 130 mV for a silver-silver chloride electrode.

The formed nuclei are allowed to grow in the presence of the crystal habit controlling agent by physical ripening and through the addition of a silver salt and a halide. In this case, the chloride concentration is 5 mol/L or less, and preferably 0.05 to 1 mol/L. The temperature at the time of growth of the nuclei may be selected in the range from 10 and 90° C., but the temperature is preferably in the range from 30 to 80° C.

The total amount of the crystal habit controlling agents used is preferably 6×10^{-5} mol or more, and most preferably in the range from 3×10^{-4} to 6×10^{-2} mol per mol of silver halide in a completed emulsion. The timing of addition of the crystal habit controlling agent may be at any stage between the stage of nucleus formation and the stage of the physical ripening of the silver halide grains. After the addition of the crystal habit controlling agent, growth of (111) plane begins. The crystal habit controlling agent may be placed in a reaction vessel in advance. When small-size tabular grains are formed, the crystal habit controlling agent may be added to the reaction vessel such that its concentration will increase as the grains grow.

When the amount of a dispersion medium used at the time of nucleus formation is not sufficient for the growth of the grains, it is necessary to add the dispersion medium. It is preferable that gelatin be present in the range from 10 g/L to 100 g/L in the growth thereof. An example of gelatin to be added is preferably gelatin phthalate or trimellitic acid-added gelatin.

The value of pH at the time of nucleus formation may be arbitrarily set, and preferably set in the range from a neutral region to an acid region.

Next, a description will be given of tabular grains having (100) planes. The tabular grains having (100) planes are those having (100) plane as a principal plane. The form of the principal plane is a form of a rectangle, a form of a triangle, tetragon, or pentagon with any one angle of the rectangle being omitted (that is, a right-angled triangle having the omitted angle as an apex and formed by two sides which form the angle), or a form of a tetragon, pentagon, hexagon, heptagon, or octagon with two to four angles being omitted. Assuming that the form of a rectangle with the omitted portion being complemented is a complementary tetragon, the ratio of adjacent sides of the rectangle and the complementary tetragon (the ratio between the length of a longer side and that of a shorter side) is in the range from 1 to 6, preferably in the range from 1 to 4, and more preferably in the range from 1 to 2.

The tabular grains of a silver halide emulsion, having (100) principal planes are prepared in such a manner that a silver-salt aqueous solution and a halide-salt aqueous solution are added to and mixed with a dispersion medium such as a gelatin aqueous solution while being stirred. In this case, for example, in JP-A Nos. 6-301129, 6-347929, 9-34045, and 9-96881, there has been disclosed a method in which silver iodide or iodide ion, or silver bromide or bromide ion is allowed to be present to thereby cause distortion in nuclei from difference in crystal lattice size between silver chloride and, for example, silver bromide, and crystal deficiency which imparts anisotropic growth such as screw dislocation is introduced. When the screw dislocation is introduced, two-dimensional nucleus formation on the plane is not any longer rate-controlled under a low supersaturation condition. Therefore, crystallization on the plane advances, and by introducing the screw dislocation, the tabular grains are formed. The low supersaturation condition mentioned herein shows, preferably 35% or less of an amount at the time of critical addition, more preferably 2 to 20%. It is not necessarily determined that the crystal deficiency cause screw dislocation, but it is considered that the screw dislocation be introduced at a high possibility due to a direction in which the dislocation is introduced, or imparting of anisotropic growth to the grains. It is preferable that the introduced dislocation be held so that the tabular grains be made thinner, which is disclosed in JP-A Nos. 8-122954 and 9-189977.

Further, a method for preparing (100) tabular grains with a (100) plane-forming accelerator added thereto is disclosed by using imidazoles, 3,5-diaminotriazoles (in JP-A No. 6-347928) or by using polyvinyl alcohols (in JP-A No. 8-339044). However, the present invention is not limited to the same.

Grains having a high content of silver chloride used in the present invention is grains whose silver chloride content is 80 mole % or more, preferably 95 mole % or more. The grains of the present invention preferably have a so-called core/shell structure comprised of a core section and a shell section surrounding the core section. The core section preferably contains 90 mole % or more of silver chloride. The core section may be comprised of two or more portions having different halogen compositions. The shell section preferably covers 50% or less of the total volume of the grains, most preferably 20% or less. The shell section preferably contains silver iodochloride or silver iodobromochloride. Further, the shell section preferably contains 0.5 to 13 mole % of iodine, most preferably 1 to 13 mole %. A silver iodide content of the total grains is preferably 5 mole % or less, most preferably 1 mole % or less.

The silver bromide content in the shell section is preferably higher than that in the core section. The silver bromide content is preferably 20 mole % or less, most preferably 5 mole % or less.

The silver halide grains used for the light-sensitive material of the present invention are not particularly limited in an average grain size (equivalent-sphere diameter in terms of volume), but the average grain size is preferably in the range from 0.1 to 0.8 μm , most preferably in the range from 0.1 to 0.6 μm . The equivalent-circle diameter of the tabular grains is preferably in the range from 0.2 to 1.0 μm . The equivalent-circle diameter of the silver halide grains mentioned herein is a diameter of a circle whose area is equal to a projected area of the grain in an electron micrograph. Further, the thickness of the grain is 0.2 μm or less, preferably 0.15 μm or less, and particularly preferably 0.12 μm or less. In the present invention, 50% or more of the projected area of all the silver halide grains containing yellow dye-forming couplers has an average aspect ratio (that is, the ratio of the diameter to the thickness of the grains) of 2 or more, preferably 5 to 20.

Generally, the tabular grains are those having two parallel planes. Accordingly, the "thickness" mentioned in the present invention is represented by a distance between the two parallel planes which form the tabular grain.

The grain size distribution of the silver halide grains used in the present invention may be polydisperse or monodisperse, but it is more preferably monodisperse. Particularly, the coefficient of variation in an equivalent-circle diameter of tabular grains which cover 50% or more of the total projected area is preferably 20% or less, and desirably 0%.

EXAMPLES

The present invention will be hereinafter described in accordance with the following examples, but the embodiment of the present invention is not limited to the same.

In the description of examples given below, a blue sensitive emulsion layer, a green sensitive emulsion layer, and a red sensitive emulsion layer are referred to as a yellow-coupler containing layer, a magenta-coupler containing layer, and a cyan-coupler containing layer, respectively, according to circumstances. Further, after developing processing, these emulsion layers are referred to as a yellow coloring layer, a magenta coloring layer, and a cyan coloring

layer, respectively. Still further, these emulsion layers may be represented simply as BL, GL, and RL, respectively.

Example 1

5 (1) Preparation of samples of light-sensitive materials

A sample 111 of example 1 disclosed in JP-A No. 11-24217 was prepared and formed into a roll having a transverse dimension of 254 mm, to thereby prepare a sample 101.

10 Next, samples 102 and 103 were prepared from the sample 101 by making a change in components of a light-sensitive material shown below.

1. Alteration of blue sensitive silver halide emulsion

Sample 102:

A sample 102 of light-sensitive material was prepared by using the same emulsions as those of the sample 101, except that a silver chlorobromide emulsion A which is a yellow-coupler containing layer in the sample 101 was changed to the following emulsion A-II.

Sample 103:

A sample 103 of light-sensitive material was prepared by using the same emulsions as those of the sample 101, except that a silver chlorobromide emulsion A which is a yellow-coupler containing layer in the sample 101 was changed to the following emulsion A-III.

<Preparation of emulsions>

Preparation of emulsion A-II [(111) tabular grains having a high content of silver chloride (average grain size: 0.46 μm)]

2.0 g of sodium chloride and 2.8 g of inert gelatin were added to 1.2 L of water in a vessel and was kept at 33° C. To this solution, 45 cc of a silver nitrate aqueous solution (18 g of silver nitrate) and 45 cc of a sodium chloride aqueous solution (6.4 g of sodium chloride) were added, while being stirred, in double jets for 1 minute. 1 minute after completion of the addition, 0.8 millimole of the following crystal habit controlling agent 1 and 560 g of a gelatin phthalate aqueous solution (10%) were added. Then, 1 minute later, 3.0 g of sodium chloride was added to the mixture. The temperature of a reaction vessel was heated up to 60° C. over 25 minutes, and the mixture was ripened at 60° C. for 16 minutes. Thereafter, 3 g of sodium chloride and 1×10^{-5} mole of sodium thiosulphonate were added to the above mixture. To the mixture, 295 cc of a silver nitrate aqueous solution (18 g of silver nitrate), 295 cc of a sodium chloride aqueous solution (containing 50.3 g of sodium chloride and 2×10^{-8} mole of iridium hexachloride), and 160 cc of an aqueous solution of the crystal habit controlling agent 1 (M/50) were added over 13 minutes at an increased flow rate. 2 minutes later, a silver nitrate aqueous solution (34 g of silver nitrate) and a sodium chloride aqueous solution (containing 11.6 g of sodium chloride and 1.27 mg of yellow prussiate of potash) were further added over 5 minutes. Then, 33.5 cc of a 0.1N thiocyanic acid solution, 0.32 millimole of a sensitizing dye J, 0.48 millimole of a sensitizing dye K, and 0.05 millimole of a sensitizing dye L were added to the mixture.

The mixture was cooled down to 40° C. and demineralized by an ordinary flocculation method. After water washing, 67 g of gelatin, 80 cc of phenol (5%), and 150 cc of distilled water were added, and pH was controlled to 6.2 and pAg was controlled to 7.5 with caustic soda and a silver nitrate solution.

60 The ratio of tabular grains to total grains was 90% or more of the total projected area of all the obtained grains, and the average equivalent-circle diameter was 0.71 μm , the average thickness was 0.13, and the average equivalent-sphere diameter was 0.46 μm .

Crystal habit controlling agent 1

(2) Preparation of Emulsion A-III [(100) tabular grains having a high content of silver chloride (average grain size: 10 0.47 μm)]

1.2 L of water, 25 g of gelatin (deionized alkaline-treatment bone gelatin whose methionine content is about 40 $\mu\text{mol/g}$), 0.4 g of sodium chloride, and 4.5 ml of a solution of nitrate (1N) were placed in a reaction vessel (pH: 4.5) and kept at 40° C. To the mixture, an Ag-1 solution (silver nitrate is contained at the rate of 0.2 g/cc) and an X-1 solution (sodium chloride is contained at the rate of 0.069 g/cc) were added and mixed for 4 minutes at the rate of 48 cc/min. while being strongly stirred. 15 seconds later, 150 ml of a polyvinyl alcohol aqueous solution (containing 6.7 g of polyvinyl alcohol (PVA-1) in which an average degree of polymerization of vinyl acetate is 1700 and an average saponification rate for alcohol is 98% or more, and also containing 1 L of H₂O) was further added. 15

20

To the obtained mixture, 12.3 ml of a solution of nitrate (1N) was added and pH was controlled to 3.5. The mixture was heated up to 75° C. over 15 minutes, and 23 ml of a solution of sodium hydroxide (1N) was added and pH was controlled to 6.5. To the mixture, 4.0 ml of 1-(5-methylureidophenyl)-5-mercaptopurine (0.05%) and 4.0 ml of N,N'-dimethylimidazoligene-2-thion (1% aqueous solution) were added. 4 g of sodium chloride was added and a silver potential (against a room-temperature saturated calomel electrode) was adjusted to 100 mV. Thereafter, an Ag-1 solution and an X-1 solution were added simultaneously for 15 minutes, so as to allow growth of grains, while the flow rate being increased linearly from 40 cc/min. to 42 cc/min. with the silver potential being kept at 100 mV. To the obtained mixture, 12.5 ml of a solution of nitrate (1N) was added and pH was controlled to 4.0. 28.8 g of sodium chloride was added and the silver potential was controlled to 60 mV, and thereafter, 0.38 millimole of a sensitizing dye J, 0.56 millimole of a sensitizing dye K, and 0.06 millimole of a sensitizing dye L were added and an Ag-2 solution (silver nitrate: 0.1 g/cc) and an X-2 solution (sodium chloride: 0.0345 g/cc) were added for 10 minutes at the flow rate of 40 cc/min., and thereafter, the mixture was allowed to stand for 10 minutes at 75° C. 30

35

Thereafter, the resulting mixture was washed by precipitation at 40° C., and was thereby demineralized. 79 g of gelatin was added to disperse again the emulsion, and pH was controlled to 6.0 and pAg was controlled to 7.3. Then, a portion of the emulsion was sampled and an electron photomicrographic image (TEM image) of a replica of the grains was observed. As a result, the ratio of tabular grains having (100) plane as a principal plane to total grains was 90% of the total projected area of all the AgX grains, and the average equivalent-sphere diameter was 0.47 μm , the average grain thickness was 0.10 μm , and the average aspect ratio was 7.8, and the average adjacent edge ratio was 1.2. 40

Sensitizing dye J

Sensitizing dye K

Sensitizing dye L

2. Alteration of coating sequence of coloring layers and alteration of amount of gelatin

Sample 102:

In the sample 102, coloring layers were formed in the order of yellow, magenta, and cyan from the side of a substrate by changing the order in which the coloring layers are formed in the sample 101. Further, the sample 102 was prepared in the same way as in the sample 101, except that a total amount of gelatin is changed from 7.12 to 5.69 g/m² by reducing an amount of a gelatin binder of each of other layers than the yellow-coupler containing layer in the sample 101 by 25%. 40

Sample 103:

The sample 103 was prepared in the same way as in the sample 101, except that a total amount of gelatin is changed from 7.12 to 5.69 g/m² by reducing an amount of a gelatin binder of each of other layers than the yellow-coupler containing layer in the sample 101 by 25%. 50

(2) Developing processing and evaluations

1. Exposure and processing conditions for color paper

A human figure was photographed at the center of a background of outdoors and fine weather on a commercial color negative film (Fuji Color Negative Film Super 400 manufactured by Fuji Photo Film Co., Ltd.), and the color film was subjected to developing processing using an automatic processor FP-363SC manufactured by Fuji Photo Film Co., Ltd., and a color negative film processing formula CN-16S and its processing chemicals (which are both manufactured by Fuji Photo Film Co., Ltd.). 55

Image information was read from the developed color negative film by an input device/scanner-image processor SP1500 (manufactured by Fuji Photo Film Co., Ltd.), and the sample 102 was exposed by a laser exposure unit using the processing apparatus of the present embodiment shown in FIG. 2, and running processing was carried out by 60

processes and processing solutions, which will be described later, until an accumulated amount of replenishment of a developing solution becomes three times the capacity of the tank.

A mini-lab printer processor PP728 manufactured by Fuji Photo Film Co., Ltd. was used as a comparative processor in carrying out the running processing. The processor PP728 was modified so that a processing time can be arbitrarily changed. The sample 102 was exposed by a plane exposure unit installed in the processor PP728 using the above-described developed color negative film, and the running processing was carried out in the same processes and processing solutions as those of the present embodiment.

Process	Temperature	Time	Replenisher*	Tank capacity
Color development	45° C.	15 seconds	35 ml	1.5 L
Bleach-fix	40° C.	15 seconds	35 ml	1.5 L
Rinsing 1	40° C.	4 seconds	—	0.5 L
Rinsing 2	40° C.	4 seconds	—	0.5 L
Rinsing 3	40° C.	4 seconds	—	0.5 L
Ringing 4	40° C.	8 seconds	180 ml	1.0 L
Drying	85° C.	10 seconds		

*An amount of replenisher is indicated by an amount per square meter of light-sensitive material.

The rinsing process is effected by using four tanks and these tanks are formed as a countercurrent flow system from the fourth to the first one.

The compositions of the processing solutions are described below.

Color developing solution:	(in a tank)	(to be replenished)
water	800 ml	800 ml
triisopropanolamine	0.2 mol	0.2 mol
ethylenediamine tetraacetate	4.0 g	4.0 g
4,5-dihydroxybenzene-1,3-disodium disulphonate	0.5 g	0.5 g
potassium chloride	15.8 g	—
potassium bromide	0.045 g	—
sodium sulfite	0.1 g	0.1 g
fluorescent whitening agent Hakkol FWA-SF (manufactured by Showa Chemical Industry Co., Ltd.)	4.0 g	8.0 g
sodium p-toluenesulfonate	20.0 g	20.0 g
disodium-N,N-bis(sulfonatoethyl)hydroxylamine	20.0 g	20.0 g
N-ethyl-N-(β-methanesulfonamidethyl)-3-methyl-4-aminoaniline · 3/2 sulfate monohydrate	6.0 g	24.0 g
potassium carbonate	26.3 g	26.3 g
addition of water	1000 ml	1000 ml
pH (25° C./adjusted by potassium hydroxide)	10.35	12.60

Bleach-fixing solution:	(in a tank)	(to be replenished)
water	500 ml	500 ml
ammonium thiosulfate (75%)	104 ml	193 ml
ethylenediamine tetraacetatic acid	3.2 g	5.9 g
ethylenediamine tetraacetatic acid, iron (III)	62.0 g	124.0 g
ammonium salt dihydrate	58.0 g	116.0 g
ammonium sulfite monohydrate	10.0 g	20.0 g

-continued

5	Bleach-fixing solution:	(in a tank)	(to be replenished)
n-butylguanidine half sulfate	6.6 g	14.8 g	
succinic acid (50%)	24.0 g	44.0 g	
addition of water	1000 ml	1000 ml	
pH (25° C.: adjusted by nitric acid)	5.50	4.98	

10 Rinsing solution (a solution contained in the tank and a solution to be replenished have the same composition)

15	chlorinated sodium isocyanurate deionized water (conductivity: 5 μ s/cm or less) pH	0.2 g 1000 ml 6.5

2. Evaluation of photographic properties

20 After completion of the running processing, developing processing was carried out after a continuous tone wedge exposure was applied to the sample 101 using a sensitometer (manufactured by Fuji Photo Film Co., Ltd., FW type, color temperature of a light source is 3200K, exposure time is 0.1 second, and an amount of exposure is 250 CMS). Further, as shown in FIG. 5, the developing processing was carried out by changing the roller diameter to 12.5 ϕ , 15 ϕ , and 20 ϕ . The density of the developed sample was measured and the maximum density portion (Dmax) measured by blue light (filter light corresponding to status A) was read from the characteristic curve. The results are shown in FIG. 5. In this figure, a desired photographic property (density) is a value obtained by the mini-lab printer processor PP728 manufactured by Fuji Photo Film Co., Ltd., which is used as the comparative processor.

30 It can be seen from FIG. 5 that no-jamming conveying property is maintained (a conveying torque of approximately 1 kg or more is required) and the desired photographic property can be obtained by the present embodiment. The desired photographic property mentioned herein means an agitation effect of the processor. The sample 101 in the above-described processing conditions is in a state of being subjected to developing processing, and the density B of the lowermost layer is influenced by the agitation. Accordingly, 40 it can be seen from FIG. 5 that the agitation ability of the present embodiment is higher than the ability of the comparative processor and the present embodiment is excellent in rapidity of the processing.

35 Example 2

50 After completion of the running processing of Example 1, photographic property and conveying property were evaluated in the following procedure.

1. Evaluation of photographic properties

55 After completion of the running processing, developing processing was carried out under experimental conditions shown in Table 1 with the samples 102 and 103 being exposed in the same manner as in Example 1.

The densities of the developed samples were measured 60 and the maximum density portion (Dmax) measured by blue light (filter light corresponding to status A) was read from the characteristic curve.

65 The photographic property was evaluated by calculating the following expression on the basis of respective values of the samples in the mini-lab printer processor PP728 manufactured by Fuji Photo Film Co., Ltd., which was used as the comparative processor.

15

If the value of $\Delta D_{max}(B)$ is positive, the ability of agitation higher than that of the comparative processor is realized, which is shown as a preferred embodiment.

$$\Delta D_{max}(B) = [D_{max}(B) \text{ in each experimental condition}] - [D_{max}(B) \text{ in PP728}]$$

2. Evaluation of conveying property

After completion of the running processing, a gray wall was photographed at a standard amount of exposure in the state of being illuminated by a light source of standard C mentioned in ISO5800 (sensitometry of color negative film) on a Fuji Color Negative Film Super 400 (manufactured by Fuji Photo Film Co., LTD.), and the samples **102** and **103** which are cut in quarters (which are each 254 mm×305 mm) were exposed in the same manner as in Example 1 and continuous processing was carried out every 50 sheets under the conditions shown in Table 1.

The conveying property was evaluated for the obtained color prints on the basis of the following criteria:

- : no damage such as separation of coating was found at ends of the prints;
- Δ: damage was found at ends of 1 to 20 sheets of prints among 50 sheets, but no problem is offered in practical use;
- X: damage was found at ends of 21 to 50 sheets of prints among 50 sheets, and a problem is offered in practical use; and
- XX: damage was found at ends of all the 50 sheets of prints, and jamming was also caused.

TABLE 1

Experimental condition	Sample	Roller diameter	Photographic property $\Delta D_{max}(B)$	Conveying property	Note
1	102	8 mm	+0.03	○	Comp. ex.
2	102	12.5 mm	+0.03	○	Present invention
3	102	15 mm	+0.03	○	Present invention
4	102	20 mm	+0.02	○	Present invention
5	102	25 mm	-0.06	○	Comp. ex.
1	103	8 mm	+0.04	X	Comp. ex.
2	103	12.5 mm	+0.03	Δ	Present invention
3	103	15 mm	+0.02	○	Present invention
4	103	20 mm	+0.01	○	Present invention
5	103	25 mm	-0.07	○	Comp. ex.

Note: "Comp. ex." means comparative example.

It can be seen from Table 1 that the photographic property (desired agitation ability) and the conveying property are compatible with each other by the present embodiment. Further, it can also be understood that combination of the processing apparatus according to the present invention and the sample **102** allows compatibility between the photographic property and the conveying property in a more stabilized region.

The present invention thus provides the above-mentioned structure and method, and therefore, the desired photographic properties can be obtained and the apparatus can be made small in size.

What is claimed is:

1. A developing processing apparatus equipped with at least one blowoff chamber having jetting holes from which

16

a processing solution is jetted toward an emulsion surface of a photosensitive material, wherein the one blowoff chamber is disposed in a processing tank, roller sets are located at both sides of the blowoff chamber, the photosensitive material is horizontally conveyed above the blowoff chamber, and positions where the photosensitive material is nipped by the roller sets are located within the processing solution.

2. A developing processing apparatus according to claim 1, wherein the roller sets are formed integrally with a processing rack set in the processing tank.

3. A developing processing apparatus according to claim 2, wherein the blowoff chamber is, together with the roller sets, formed integrally with the processing rack.

4. A developing process apparatus according to claim 1, wherein the roller sets, respectively, have an upper roller and a lower roller, and wherein a diameter of each of the upper rollers is in a range of 10 mm to 20 mm and a diameter of at least one of the lower rollers is less than or equal to that of a corresponding one of the upper rollers, and a dimension of the blowoff chamber in a direction in which the photosensitive material is conveyed is in a range of 50 mm to 120 mm.

5. A developing process apparatus according to claim 2, wherein the roller sets, respectively, have an upper roller and a lower roller, and wherein a diameter of each of the upper rollers is in a range of 10 mm to 20 mm and a diameter of at least one of the lower rollers is less than or equal to that of a corresponding one of the upper rollers, and a dimension of the blowoff chamber in a direction in which the photosensitive material is conveyed is in a range of 50 mm to 120 mm.

6. A developing process apparatus according to claim 3, wherein the roller sets, respectively, have an upper roller and a lower roller, and wherein a diameter of each of the upper rollers is in a range of 10 mm to 20 mm and a diameter of at least one of the lower rollers is less than or equal to that of a corresponding one of the upper rollers, and a dimension of the blowoff chamber in a direction in which the photosensitive material is conveyed is in a range of 50 mm to 120 mm.

7. A developing processing apparatus according to claim 1, wherein an interval between the jetting holes of the blowoff chamber and the photosensitive material is in a range of 2.0 mm to 20.0 mm.

8. A developing processing apparatus according to claim 1, wherein a hole diameter of each of the jetting holes of the blowoff chamber is in a range of 0.5 mm to 0.9 mm.

9. A developing processing apparatus according to claim 1, wherein the jetting holes of the blowoff chamber are arranged at intervals of 3.0 mm to 4.5 mm in a longitudinal direction of a jetting panel of the blowoff chamber, that is, in a transverse direction of the photosensitive material.

10. A developing processing apparatus according to claim 1, wherein the jetting holes are disposed in plural rows, and adjacent three rows of the jetting holes are located at different positions from each other to form the staggered arrangement, and the three rows of holes are formed repeatedly on a jetting panel.

11. A developing processing apparatus according to claim 1, wherein developing processing time is in a range of 10 to 15 seconds and conveying speed is in a range of 7 to 20 mm/s.

12. A developing processing method in which a processing solution is jetted toward an emulsion surface of a photosensitive material by a blowoff chamber having jetting holes formed therein, wherein the one blowoff chamber is disposed in a processing tank and the photosensitive material is

processed while being horizontally conveyed above the blowoff chamber by roller sets, which are disposed at both sides of the blowoff chamber and are formed in such a manner that positions where the photosensitive material is nipped by the roller sets are located within the processing solution.

13. A developing processing method according to claim 12, wherein the roller sets are formed integrally with a processing rack set in the processing tank.

14. A developing processing method according to claim 13, wherein the blowoff chamber is, together with the roller sets, formed integrally with the processing rack.

15. A developing process method according to claim 12, wherein the roller sets, respectively, have an upper roller and a lower roller, and wherein a diameter of each of the upper rollers is in a range of 10 mm to 20 mm and a diameter of at least one of the lower rollers is less than or equal to that of a corresponding one of the upper rollers, and a dimension of the blowoff chamber in a direction in which the photo-sensitive material is conveyed is in a range of 50 mm to 120 mm.

16. A developing process method according to claim 13, wherein the roller sets, respectively, have an upper roller and

5 a lower roller, and wherein a diameter of each of the upper rollers is in a range of 10 mm to 20 mm and a diameter of at least one of the lower rollers is less than or equal to that of a corresponding one of the upper rollers, and a dimension of the blowoff chamber in a direction in which the photo-sensitive material is conveyed is in a range of 50 mm to 120 mm.

10 17. A developing process method according to claim 14, wherein the roller sets, respectively, have an upper roller and a lower roller, and wherein a diameter of each of the upper rollers is in a range of 10 mm to 20 mm and a diameter of at least one of the lower rollers is less than or equal to that of a corresponding one of the upper rollers, and a dimension of the blowoff chamber in a direction in which the photo-sensitive material is conveyed is in a range of 50 mm to 120 mm.

15 18. A developing processing method according to claim 12, wherein a hole diameter of the jetting holes of the blowoff chamber is in a range of 0.5 to 0.9 mm.
